[57] CLAIM

The ornamental design for a toy glider, as shown and described.

DESCRIPTION

FIG. 1 is a top plan view of a toy glider showing my new design;

FIG. 2 is a front elevational view thereof;

FIG. 3 is a rear elevational view thereof;

FIG. 4 is a side elevational view thereof, the opposite side being a mirror image thereof;

FIG. 5 is a perspective view thereof;

FIG. 6 is a bottom plan view thereof;

FIG. 7 is a top plan view of a second embodiment of FIG. 1, the difference residing in the length of the wings; and,

FIG. 8 is a front elevational view of FIG. 7.

FIG. 1

FIG. 2

FIG. 3

FIG. 4

FIG. 5

FIG. 6

FIG. 7

FIG. 8
